UNITED STATES PATENT OFFICE.

EDWARD A. CUNNIF, OF WALTHAM, MASSACHUSETTS, ASSIGNEE TO DRAPER CORPORATION, OF HOPEDALE, MASSACHUSETTS, A CORPORATION OF MAINE.

FEELER MECHANISM FOR LOOMS.

Application filed December 24, 1926. Serial No. 156,879.

This invention relates to feeler mechanisms for looms whereby the operative condition of the loom is changed from time to time, such, for instance, as replenishing filling. It is now the ordinary practice to provide a feeler mechanism at the non-replenishing side of the loom, and one good type of such mechanism has been found in practice to consist of a feeler mechanism wherein the feeler itself shall enter the shuttle at an inclination to the longitudinal axis thereof to feel for the filling. A feeler mechanism of this general type lends itself readily to adaptation for different kinds or characters of filling, and likewise, to different speeds of the loom.

In accordance with the present invention, therefore, the feeler mechanism is mounted at the replenishing side of the loom, and consists of a feeler pivotally mounted upon a slide to enter the shuttle at an inclination to the longitudinal axis thereof and to be displaced towards the tip of the bobbin by the forward pressure when the filling is substantially exhausted. Inasmuch as the feeler mechanism is located at the replenishing side of the loom, it is desirable to withdraw the feeler from the shuttle during replenishment, in order to permit the entrance of a fresh supply of filling.

Since the feeler enters the shuttle at an inclination to the longitudinal axis and is held by the filling from displacement towards the tip of the bobbin while a working supply of filling is in the shuttle, and is displaced longitudinally of the filling carrier when the filling is substantially exhausted, it becomes desirable that the inclination of the feeler may be varied in accordance with the character or kind of yarn being employed, and one of the important features of the present invention therefore consists in a feeler mechanism wherein the feeler is pivotally mounted upon a slide and is held in an initial inclined position to contact with the filling and enter the shuttle at an inclination to the longitudinal axis thereof, in accordance with the character of the yarn in use and the speed of the loom.

The invention and novel features thereof will best be made clear from the following description and the accompanying drawings of one good form thereof.

In the drawings:

Fig. 1 is a perspective view at the replen-

ishing side of a loom having the present invention associated therewith;

Fig. 2 is an enlarged plan view showing the relation of parts when the feeler is displaced longitudinally of the shuttle by the frontward pressure when the filling is substantially exhausted; and

Fig. 3 is a similar view with parts omitted, showing the feeler as having been withdrawn from the shuttle to permit the entrance of the fresh filling carrier.

The loom frame and the usual operating parts may be of well-known type, and mounted upon the loom frame or a support connected thereto is the feeler stand 1 which may be associated with the loom frame by means of a bolt 2 and nut 3. The feeler stand 1 is normally under the influence of a spring 4 acting downwardly and limited in its action by means of a threaded bolt 5 extending upwardly to the feeler stand.

Mounted upon the loom frame is the bracket 6 having the slot 7 in which the end 8 of an actuator 9 is movable, said actuator being pivotally mounted at 10, and when interrupted in its movement in the slot 7, adapted to call for replenishment of filling. These features, however, are of usual construction and operate in the usual way to call for replenishment of filling when the actuator 9 is arrested in its movement in the slot 7, and need no further description.

Mounted upon the loom frame or a stand connected thereto is the stud or shaft 11 on which is pivotally mounted the transfer 90 rer 12, about the hub portion of which is the spring 13 which acts normally upon the transfer, as usual, to maintain it in its upper or inoperative position.

The filling carriers or bobbins to be transferred to the shuttle may be supported in any usual form of hopper or magazine, which, in the present illustration of the invention, comprises the rotary hopper 14 which successively moves the filling carriers 15 to 100 transferring position. This magazine may also be of usual character now well understood in the art.

Mounted upon the feeler stand 1 is the slide 16 normally under the influence of a spring 17 tending to move the slide rearwardly. The spring 17 as shown is preferably placed about the stem 18 which passes through the abutment 19 and normally acts between the front wall 20 and the project- 110

tion 19 to urge the slide 16 into its rearward position. A suitable stop may be employed to limit the rearward movement of the slide 16 and, as shown, consists of a shoulder 21 formed on the feeler stand, against which the stop 22 of the slide may contact when the slide is in its rearward position.

Mounted in the arms 23 and 24 is the shaft 10 25 to which is secured the upwardly extending finger 26, the upper end portion of which normally rests against the adjustable member 27 secured to the slide. A spring 28 placed about the shaft 25 normally acts to 15 hold the finger 26 against the stop 27.

Adjustably secured to the shaft 25 is the upwardly extending arm 29 to which is pivotally connected at 30 the rod 31 which extends rearwardly and normally projects 20 across the opening 7 of the bracket 6 to interrupt the movement of the actuator 9.

To protect the parts of the slide from the accumulation of lint and accidental displacement by unauthorized interference, the 25 feeler stand 1 has secured thereto the cover 32, which may be appropriately secured to the slide support by means of the bolts 33.

Extending downwardly from the hub of the transferer 12 is the arm 34 to which is 30 pivotally connected at 35 the dog 36 adapted to be engaged by a bunter 37 on the lay when the dog is raised into operative position through the actuation of the actuator, as common in this general type of loom.

35 The pivotal connection 35 between the arm 34 and the dog 36 is extended, as indicated in Fig. 1, to engage the lug 37 extending from the slide 16, so that on replenishment of filling the pin 35 will engage the lug 37 and 40 withdraw the slide forwardly to thereby remove the feeler from the shuttle to permit the entrance of the fresh filling carrier.

Pivoted on the slide 16 at 38 is the feeler 39 which extends rearwardly 45 from the slide in an inclined direction to enter the shuttle and feel for the filling at an angle to the longitudinal axis thereof. The filling engaging or rear end of the feeler is provided with a toothed surface, as indicated more particularly in Figs. 1 and 2, the teeth of which sink into the filling when a working supply is in the shuttle on a detecting beat and prevent longitudinal movement 50 of the feeler along the filling, but when the filling is substantially exhausted and its amount is no longer sufficient to hold the feeler, the latter will slide longitudinally of the filling carrier in the shuttle under the 55 frontward pressure upon it to effect replenishment of filling.

60 The feeler 39 has a heel portion 40 provided with a shoulder 41, which, when the feeler is in its desired feeling position, engages a suitable stop, as will be further described. The heel portion 40 is rounded, as

shown, and is preferably supported between the upper and lower walls of the slotted end portion of the slide 16. Mounted upon the slide 16 is the pin 42 about which is coiled at 43 one end portion of a leaf spring 44, 70 the free end portion whereof is connected at 45 with a pin 46 extending upwardly from the feeler 39, the construction being such that the leaf spring normally tends to throw the feeler in one direction, and is limited in its 75 movement of the feeler by means of a pin or stop 47, the construction being such that the feeler under the coacting influence of the leaf spring 44 and the stop pin 47 and the shouldered heel portion of the feeler is maintained in a position inclined to the longitudinal axis of the shuttle, so that the feeler will enter the shuttle at an inclination to the longitudinal axis thereof and feel for the filling. 80

Under different speeds of the loom and in the use of different kinds of characters of filling, the inclination of the feeler should be varied to accommodate it to the prevailing conditions, and the present invention 90 therefore provides that the stop pin 47 and the coacting shouldered portion 41 of the feeler may be relatively adjusted or positioned for determination of the inclination of the feeler in its normal feeling position. Such 95 relative adjustment of position may be secured in various ways, but in accordance with the present invention, the slide 16 is provided with a number of pin holes 48 into which the pin 47 may be positioned in order to locate the pin relative to the heel stop 41 so as to maintain the feeler in its desired 100 inclination to the longitudinal axis of the shuttle and in conformity with the speed of the loom and the character of filling employed. 105

The lay 49 is provided with the usual shuttle box at the replenishing side of the loom, the front wall 50 of which has an opening 51 which registers with a corresponding opening in the adjacent wall 52 of the shuttle 53 when the latter is properly positioned in the replenishing box, the two 110 openings affording an entrance for the inclined feeler 39 as the lay beats up.

115 It has been found in practice that the employment of a leaf spring such as 44 in connection with an incline, such as hereinbefore described, affords delicate and responsive means for determining the presence or absence of a working supply of filling in the shuttle, and by the variations in the inclination of the feeler in accordance with the speed of the loom or the character of the filling employed, the delicacy of feeler action at the replenishing side of the loom is such that its sensitiveness is manifested both as to the presence or substantial absence of filling, and on the occurrence of such substantial absence the inclined feeler is dis- 120 125 130

placed laterally by the forward pressure to cause the actuator to actuate replenishment of filling. Since the feeler at such times projects into the shuttle, it is necessary to remove it to permit the fresh filling carrier to be inserted, and on operation of the transerrer the pin 35 acts upon the projection 37 to withdraw the slide 16 forwardly and perforce withdraw the feeler 10 from the shuttle.

What is claimed is:

1. In a filling replenishing loom, the combination of a feeler stand supported by the loom frame at the replenishing side of the loom, a slide mounted on the feeler stand, a single inclined feeler pivotally mounted on the feeler stand to enter the shuttle in a direction inclined to the longitudinal axis thereof and held from displacement towards the tip of the bobbin by engagement with the filling until substantial exhaustion thereof, a leaf spring between the feeler and slide having its end normally acting laterally upon the feeler to maintain it in inclined relation to the longitudinal axis of the shuttle, an adjustable stop pin on the slide to variably limit the action of the leaf spring, filling replenishing means controlled by the forward movement of the slide and constructed to initiate replenishment of filling when the feeler is displaced toward the tip of the bobbin to thereby relieve the slide from a forward thrust, and means for withdrawing the feeler from the shuttle during replenishment of filling.

2. In a filling replenishing loom, the combination of a feeler stand supported from the loom frame at the replenishing side thereof, a slide mounted on the stand, a feeler pivotally mounted on the slide and extending rearwardly to enter the shuttle in a direction inclined to the longitudinal axis thereof and held from movement longitudinally of the shuttle by engagement with the filling until substantial exhaustion thereof, and constructed to relieve the slide from a forward thrust when the feeler slides

along the filling carrier, a spring carried by the slide and having its free end secured to the feeler, a shouldered heel carried by the feeler forward of its pivotal connection with the slide, a pin on the slide for engagement with the shouldered heel of the feeler to coact with the spring and normally position the feeler in an inclined position, filling replenishing means controlled by the forward movement of the slide and constructed to initiate replenishment of filling when the feeler is displaced toward the tip of bobbin to thereby relieve the slide from a forward thrust, and means for withdrawing the feeler from the shuttle on replenishment of filling.

3. In a filling replenishing loom, the combination of a feeler stand supported from the loom frame at the replenishing side thereof, a slide mounted on the stand, a feeler pivotally mounted on the slide and extending rearwardly to enter the shuttle in a direction inclined to the longitudinal axis thereof and held from movement longitudinally of the shuttle by engagement with the filling until substantial exhaustion thereof, a spring carried by the slide and having its free end secured to the feeler, a shouldered heel carried by the feeler forward of its pivotal connection with the slide, a pin on the slide for engagement with the shouldered heel of the feeler to coact with the spring and normally position the feeler in an inclined position, means permitting adjustment of the pin to different positions to vary the angle of inclination of the feeler, filling replenishing means controlled by the forward movement of the slide and constructed to initiate replenishment of filling when the feeler slips lengthwise of the filling carrier, and means for withdrawing the feeler from the shuttle on replenishment of filling.

In testimony whereof, I have signed my name to this specification.

EDWARD A. CUNNIF. 90
